WATER COOLED INSULATOR

Barton H. Roffee, Oak Ridge, Tenn., assignor to
the United States of America as represented
by the United States Atomic Energy Commis-
sion

Application November 30, 1944, Serial No. 566,006

3 Claims. (Cl. 174—15)

1

This invention relates to insulating devices and is particularly concerned with an insulator having cooling means associated therewith so as to limit the temperature to which the material of the insulator rises under operating conditions.

The invention finds particular application in connection with insulators employed under conditions of service of the severest kind such as ordinarily will tend to cause the insulators to fail unless adequate provisions are made to withstand the severe conditions of service. These particularly severe conditions of service are apt to be encountered in isotope separating apparatus wherein the insulating devices are subjected to relatively high temperatures and at the same time are operating in conditions of high vacuum, are exposed to a relatively intense magnetic field and also may be subjected to considerable mechanical stresses. Conditions of high temperature are perhaps the factor most apt to bring about failure of the insulating device, and it is therefore highly desirable that means be provided to cool the insulator so as to limit the temperature to which the material of the insulator will rise. This is particularly true since with various insulating materials such as, for example, ceramic there is a critical temperature at which this material is no longer an insulator. If this temperature is reached, the insulators have, of course, failed, and furthermore at extremely high temperatures the structure of the material changes to some extent, and some of its mechanical strength is lost. My invention is particularly concerned with insulators of the stand-off type, that is, insulators which are used as a spacer between devices between which there is relatively wide difference in potential.

An object of my invention is to provide means for cooling an insulator without materially lessening the mechanical strength of the insulator and without lessening its effectiveness as an insulator. This objective is achieved in part by providing cooling means which do not necessitate that there be a bore extending throughout the length of the insulator.

Another object of the invention is to provide an insulator cooled by means of having a fitting secured in a depression in the material of the insulator and arranged so that cooling medium may be caused to flow into and out of the fitting.

Another object is to provide a cooling arrangement as stated in the previous objective including an additional arrangement whereby the cooling medium being admitted to the fitting can also circulate substantially circularly with refer-

2

ence to the fitting and the insulator so as to provide a maximum of cooling effect in the vicinity of the cooled portion of the insulator.

Another object of the invention is to provide an insulator having cooling means as in the previous object wherein the means for cooling are provided at a plurality of places with reference to the insulator, and particularly at the opposite ends of the insulator.

10 Further objects of the invention and numerous of its advantages will become apparent from the following detailed description and annexed drawing wherein Fig. 1 is a cross-sectional view of the insulator, the left end of Fig. 1 being a section 15 taken along the line 1—1 of Fig. 3, and the right end of Fig. 1 being a section taken along the line 1—1 of Fig. 2.

Fig. 2 is a view taken along the line 2—2 of Fig. 1.

20 Fig. 3 is an end view of the structure at the left end of Fig. 1.

In a preferred form of my invention I use ceramic as the material of the insulator. It is to be understood, of course, that other suitable materials might be used.

25 Referring to the drawings, in Fig. 1 the ceramic insulator 1 is shown supported from a supporting member or plate 2. The base of the insulator comprises a circular member 3 which is secured to the plate 2 by means of screws 4 which extend entirely through the member 3 and screw into tapped holes in a disc or ring member 5. The member 5 has a circular opening 6 therein which is counterbored as shown and fitted into the counterbore is the right end of a brass conical or dome shaped member 7 which protrudes into a similarly shaped but larger cored hole 8 formed in the ceramic insulator. The member 7 is fastened in place by means of a babbitt-like alloy poured in around the member 7 and which engages arcuate shoulders 10 on the side walls of member 7. Parts 3 and 5 are also made of brass. The alloy as shown forms a flange between the insulator and the member 5.

30 The member 3 has an annular channel 11 cut in its circumference and there is a radial channel 12 communicating with 11 and with an axial channel 13 in member 3. There is an eccentric groove or slot 14 cut in the member 3 and surrounding the axial channel 13 and this eccentric slot or groove communicates by way of a radial channel 15 with the circumference of member 3 at a point spaced 45° from the radial channel 12. (See Fig. 2.) The channel 13 is counter-bored 35 as shown, and a length of tube 16 fits into the

counterbore and extends outwardly into the dome-shaped member 7.

A tube or pipe 17 is connected to the circumferential channel 11 which is otherwise closed and sealed by a ring member 18 so that cooling medium can flow in through pipe 17 all around the channel 11 into the channel 12, the channel 13, and through the tube 16 into the interior of member 7, and then out of 7 around 16 into the eccentric channel 14, thence through the channel 15 to an outlet pipe 19 as shown. (See Fig. 2.)

Numeral 20 designates a shield soldered to the member 3.

Referring to the left end of Fig. 1 and to Fig. 3, the structure is somewhat similar, there being a cored hole 25 in the ceramic of the insulator and protruding into the cored hole and fastened therein by alloy 23 is a brass member 27 having a dome shape which is soldered to an end plate 28. The end plate has secured thereto by screws 29 as shown a ring-shaped member 29 forming a skirt, the members 28 and 29 forming a cap with the alloy forming a flange as shown between the cap and the ceramic of the insulator. The dome-shaped member 27 has a dome-shaped hollowed out portion within it, and it also has grooves or channels running around it in a plane perpendicular to its axis, these grooves being designated by numeral 30. Member 27 also has longitudinal grooves or channels designated at 31; the alloy flows into the grooves or channels just described. Member 27 seats in an appropriate annular groove in plate 28 and within the member 27 is a baffle 32 supported from plate 28, the baffle being mounted at an angle as shown, and its end being spaced from the end of member 27 to permit flow of cooling medium around the end of the baffle. Cut in the inner face of plate 28 is an arcuate groove or slot 35 of about 60° less than 360° in angular extent. Cooling medium is admitted through the tube 36 (Fig. 3) which connects with a channel 37 in plate member 28 which in turn communicates with the interior of member 27 above the baffle 32, the cooling medium flowing around the baffle and then back to another opening in plate 28 which communicates with the arcuate channel 35, the cooling medium flowing around through this channel 39 connecting with an outlet pipe 40.

It is to be seen that the arrangement provides for cooling at both ends of the insulator and the cooling is facilitated by reason of the incoming cooling medium circulating substantially circularly at each end.

From the foregoing those skilled in the art will observe that I have provided efficient means for cooling an insulating device whereby insulator failures caused by conditions such as enumerated above can be materially reduced. The mechanical arrangement is such as to not materially lessen the mechanical strength and effectiveness of the insulator, particularly since there is no bore or opening extending all of the way through the interior of the insulating member.

The foregoing disclosure is representative of a preferred form of my invention, and it is intended that the disclosure be interpreted in an illustrative rather than a limiting sense and that the scope of the invention be determined in accordance with the claims appended hereto.

I claim:

1. In an insulator of the stand-off type adapted to be mounted at one end, an elongated member made of insulating material and having a solid intermediate portion, said member having a central depression formed in one end, means comprising an end cap for the insulator having a member extending into said depression, said means being secured to said insulating material, and said end cap having passageways formed therein including passageways formed within said member including an inlet passageway extending to a point adjacent the inner end of said depression and an outlet passageway extending back through said end cap.

2. The structure of claim 1 wherein said member is hollow and has a transverse baffle member therein terminating short of the inner end of the member.

3. The structure of claim 1 wherein said member is hollow and one of said passageways is formed by a tube portion extending part way into said member and another passageway is formed between said tube portion and the interior of the member around the tube portion.
